ANESTHETIC APPARATUS

Justin G. Sholes and John T. Gleklor, Cleveland,
Ohio, assignors to The Ohio Chemical & Man-
ufacturing Company, Cleveland, Ohio, a corpo-
ration of Ohio

Application May 7, 1938, Serial No. 206,514

10 Claims. (Cl. 128—203)

This invention relates to the administration of an anesthetic gas (by which term we mean to include anesthetic vapors also) to a patient under the control of the patient himself, for the purpose of producing analgesia as distinguished from anesthesia, though it is to be understood that the administration can be controlled by the doctor,—a physician or dentist,—or by an anesthetist, to produce anesthesia of any depth desired. The chief object of the invention is to provide an apparatus which requires positive actuation by the operator to cause delivery of gas to the breathing mask, so that when operated by the patient himself a lapse into unconsciousness will prevent further inhalation of more than a limited amount of the gas at most. In such case the anesthesia is shallow and the patient quickly regains consciousness. Another object is to provide for the purpose an apparatus which requires but slight muscular exertion on the part of the patient and which can therefore be used for a considerable period at a time without undue fatigue, as for example a half-hour or more in the dentist's chair, or while the surgeon is setting a complicated fracture. A further object is to provide an apparatus which is simple in construction and unfailing in operation. Still another object is to provide a control mechanism in which the control valves are actuated by cam means in such manner that the inlet and outlet valves can not be open simultaneously, but only one at a time. To these and other ends the invention comprises the novel features of construction and combinations of elements herein-after described.

Among the various forms in which our invention can be embodied we have selected for illustration and description herein the one which we believe is the most convenient and effective. This embodiment is shown in the accompanying drawings, in which

Fig. 1 is a side elevation of the complete apparatus.

Fig. 2 is a detail sectional view on a plane indicated by line 2—2 of Fig. 3, and

Fig. 3 is a detail section on a plane indicated by line 3—3 of Fig. 2.

The apparatus shown comprises a hollow standard 10 mounted on a tripod base 11 equipped with castors 12 for convenient movement on the floor. The standard 10 carries a tubular yoke 13 supporting two gas cylinders or bottles 14, 15, one, say 15, containing an anesthetic gas and having a hand-operated valve 16 the outlet of which (not shown) opens into the yoke for de-

livery of the gas to the pressure regulator or reducing valve 17. The other cylinder, 14, may contain another anesthetic gas, but preferably it contains oxygen, for use by the doctor or anesthetist in emergencies. For this purpose it is provided with a hand valve 18, connected by a flexible tube 19 to one arm of a Y-fitting 20 the other arm of which is connected by a flexible tube 21 to a chamber 22 to receive gas therefrom as explained hereinafter. The stem of the Y-fitting is connected by a flexible tube 23 to a breathing bag 24 which is itself connected by flexible tubes 25 to the breathing mask 26. The parts 24, 25, 26 are preferably constructed as described in the copending application of J. G. 15 Sholes, Serial No. 151,569, the mask having an exhaling check valve 26a, and the bag 24 having an air-intake check valve (not shown) at 24a to permit air to enter the bag at each inhalation and at 24b a check valve (not shown) to 20 prevent exhalation into the bag. In the present instance the mask 26 is designed to fit over the patient's nose only, leaving the mouth free, as is necessary for dentistry or, in general, for work in the mouth or throat; but it may of course be 25 constructed to cover the mouth as well or the mouth only when access to the oral cavity is not required.

The pressure regulator 17 and the gas chamber 22 are connected through two valves, the 30 first, indicated at 30, being hand-operated to regulate or shut off entirely the flow of low-pressure gas to the chamber. For this purpose the operating knob 31 may have a pointer 32 to indicate by its position the setting of the valve. 35

Between valve 30 and gas chamber 22 is a gas inlet valve 35 (see also Fig. 2), comprising a housing 36 having a tubular neck fitted in the wall of the chamber and formed with a conical seat 37 for cooperating with a valve head 38 on 40 the end of a valve stem 39 movable longitudinally in the neck but urged in one direction by a coil spring 40 to press the valve head on the seat. The valve stem is guided by a thimble 41 mounted on the inner end of the neck and provided with 45 one or more openings for flow of gas into the gas chamber 22. The valve is opened to admit gas by an arm or lever 43 pivoted at 44 on a wall of chamber 22.

The gas chamber 22 is equipped with an outlet 50 valve 45 having a nipple 46, Figs. 2 and 3, for attachment of tube 21 by which gas is delivered to the bag 24. This valve is provided with a conical seat 47 to cooperate with a valve head 48 held yieldingly on the seat by a coil spring 49 through 55

which the valve stem 50 extends into the gas chamber 22. The stem is actuated to move the valve head off the seat by the arm or lever 51 pivoted at 52 on a wall of the chamber 22.

6 The two valve-operating levers 43, 51 are themselves actuated by a cam 55 mounted inside of the gas chamber 22 on a shaft 56 for rotation thereby, the shaft being mounted at one end in a bearing on the inside of the removable wall 57 and at the other in a removable bearing 58 in the opposite wall. The shaft 56, and with it the cam 55, is rotated by a pinion 59 mounted on the outer end of the shaft and meshing with a gear 60 rotatably mounted on the chamber outside of the same. The gear is rotated by an arm 61 actuated by a reciprocating rod or plunger 62 as described hereinafter.

The valve-operating cam 55, Fig. 2, is circular for the greater part of its periphery but has two rises 65, 66, adjacent to each other. Normally the cam is in the position shown in Fig. 2, with the cooperating end of the valve operating lever 43 between the rises, and with the cooperating end of lever 51 at a point opposite in the circular portion of the periphery of the cam. When, however, the gear 60 is rocked clockwise by the outward movement of rod 62 against the tension of its returning spring 62a the cam 55 is rotated counterclockwise, thereby bringing rise 66 into cooperation with the lever 43 and opening the inlet valve 35. This permits gas from regulator 17, Fig. 1, to enter the gas chamber 22. As the cam continues its counterclockwise movement rise 66 passes off the lever and the inlet valve is closed by spring 40. Further counterclockwise movement of the cam brings rise 65 into engagement with lever 51, which is thereby rocked to open the outlet valve 45 and permit gas to flow from the chamber 22 to the breathing mask 25, Fig. 1, the inlet valve 35 remaining closed. The cam is now arrested (by stop pin 67 extending from a wall of the gas chamber 22 into an arcuate slot 68 in the cam) and if the cam is held in that position the patient can continue to inhale gas until the supply available from the chamber is exhausted. Upon release of the arm 61 the spring 62a reverses the movement of the cam, in which movement cam-rise 65 passes out of engagement with the valve operating lever 51 and the outlet valve 45 closes, after which the rise 66 engages valve lever 43 and opens the inlet valve again. Finally the arm 61 reaches the upper limit of its movement, with the parts in the position shown in Fig. 2 and with both valves closed. It will be observed that the inlet valve is opened twice in each cycle of operation, thus insuring that an adequate quantity of gas under low pressure (from the regulator 17) will be delivered to the gas chamber, but it will be evident that by appropriate design of the mechanism the valve can be opened more than twice or only once in each cycle. So also the outlet valve, all without having both valves open at the same time.

The rod 62, which actuates the arm 61 to rotate the valve-operating gear 60, is itself actuated by a length of flexible shafting having a cable or wire 70 connected to the rod 62 at one end and at the other to a rod 71, Figs. 1 and 2, slidably mounted in a tubular member 72 attached to the spade-type handle 73. The rod 71 is connected to a member 74 slidably mounted in the handle 73, so that by drawing the member 74 toward the handle the patient can pull the rod 62 outwardly against the tension of spring 75 and thereby rock the cam-actuating gear 60, the

cable 70 sliding in the flexible tube 76 which may consist of a closely wound helix of stiff spring wire. When the member 74 is released the spring 75 aids the spring 62a to overcome the friction of the cable in its housing and restore the parts to the position shown in Fig. 2. The housing 76 is attached at its outer end to the tubular member 72 and at its inner end to a socket 77 removably secured to a wall of the gas chamber outside of the latter. A cover 78, 10 removably mounted on the chamber in any convenient manner, not shown, encloses the arm 61, pinion 59, gear 60, the inner end of socket 77, and the protruding end of rod 62.

If desired the interior of the gas chamber 22 15 can be connected to the interior of the hollow standard, as by means of a tube 80, Figs. 1 and 2, the connection thus making the standard a reservoir for gas delivered to chamber 22 in excess of what issues from the latter through the outlet valve 45.

To use the apparatus the sliding clamp 85, Fig. 1, is pushed toward the reservoir bag 24 far enough to permit the tubes 25 to be passed easily over the patient's head and bring the mask 26 25 into proper position on his face, after which the clamp is moved back to hold the mask comfortably in place. The patient then operates the handle 73-74 as already described, inhaling and exhaling naturally as he does so, each cycle of 30 pressure and release of part 74 opening the inlet valve 35 twice and outlet valve 45 once. At each inhalation air enters the bag at 24b along with gas from tube 23 and from the bag the mixture of gas and air passes to the mask. In exhalation the breath is discharged from the mask through the exhaling valve 26a, being prevented from entering the bag by the check valve 24a. Since the inlet and outlet valves 35, 45 can not be open simultaneously the maximum amount 40 of gas can be inhaled at any one inhalation, even though the handle be held in a position at which the outlet valve 45 is open, is determined by the setting of the pressure regulator 17 and the doctor's valve 30, either or both of which may be set 45 by the doctor himself according to his judgment as to the sensitiveness of the patient to the particular gas used. If because of too rapid operation of handle 73-74, or too rapid breathing by the patient, or from both causes, or because of 50 unknown susceptibility to the gas, the patient becomes unconscious the anesthesia so produced is shallow and the patient quickly regains consciousness, but in case of emergency the doctor can crack the oxygen valve 18 and thus deliver pure 55 oxygen to the mask. If deeper anesthesia is desired, as for example in an operation in which any sudden or convulsive movement of the patient may be dangerous, as might happen if the patient should suddenly feel pain, the doctor or 60 attendant can operate the handle and thus maintain any desired depth of anesthesia for as long as required.

It is to be understood that the invention is not limited to the specific construction herein illustrated and described but can be embodied in other forms without departure from its spirit as defined by the appended claims.

We claim—

1. In an apparatus for administration of an 70 anesthetic gas under the control of a patient, comprising, in combination, a gas chamber having means for connection with a source of anesthetic gas and means for connection with a breathing mask, an inlet valve to control the 75

- delivery of gas to the chamber, and an outlet valve operable independently of the inlet valve to control the delivery of gas to the mask, the improvements which comprise rotary cam means 5 cooperating with the valves for actuation of the same independently of each other and in succession only, so that both cannot be opened simultaneously, and means operable by the patient to actuate the cam means.
- 10 2. In an apparatus for administration of an anesthetic gas under the control of a patient, comprising, in combination, a gas chamber having means for connection with a source of anesthetic gas and means for connection with a 10 breathing mask, an inlet valve controlling the delivery of gas to the chamber, and an outlet valve controlling the delivery of gas to the mask, the improvements which comprise valve-operating means individual to the valves, rotary cam means 15 cooperating with the valve-operating means to actuate the same independently of each other and in succession only, so that both cannot be opened simultaneously, and means operable by the patient to actuate the cam means.
- 20 25 3. In an apparatus for administration of an anesthetic gas under the control of a patient, in combination, a gas chamber, means for delivering anesthetic gas thereto including an inlet valve, means for delivering gas from the chamber to a breathing mask including an outlet valve, a cam in the chamber, means actuated by the cam to open said valves independently of each other, the cam being shaped to cooperate with said means in succession only whereby the valves 30 can not be opened simultaneously, and patient-operable means outside of the chamber and operatively connected with the cam to rotate the latter.
- 40 4. In an apparatus for administration of an anesthetic gas under the control of a patient, in combination, a gas chamber, means for delivering anesthetic gas thereto including an inlet valve, means for delivering gas from the chamber to a breathing mask including an outlet valve, means housed in the chamber and including a 45 rotary cam to open said valves in succession only and prevent opening of both simultaneously, and patient-operable means outside of the chamber and operatively connected with the cam to rotate the latter.
- 50 5. In an apparatus for administration of an anesthetic gas under the control of a patient, comprising, in combination, a gas chamber, and means for delivering anesthetic gas thereto including an inlet valve, the improvements which 55 comprise means for delivering gas from the chamber to a breathing mask including an outlet valve operable independently of the inlet valve, a cam housed in the chamber, a shaft associated with the cam inside the chamber to actuate the cam and extending outside of the chamber, valve-actuating means individual thereto inside of the chamber and cooperating with the cam for actuation thereby to open the valves in succession 60 only, so that both valves cannot be opened simultaneously, and patient-operable means outside of the chamber and operatively connected with the shaft to actuate the same.
- 65 70 6. In an apparatus for administration of an anesthetic gas under the control of a patient, in combination, a gas chamber having means for connection with a source of anesthetic gas and means for connection with a breathing mask, an inlet valve to control the delivery of gas to the 75 chamber, an outlet valve to control the delivery
- or gas to the mask, valve-operating members individual to the valves, a cam to actuate the valve-operating members the cam having actuating rises individual to the valve-operating members whereby the valves can be opened in succession only and neither can be open while the other is open, and means operable by the patient to actuate the cam.
7. In an apparatus for the administration of an anesthetic gas under the control of a patient, comprising, in combination, a chamber having inlet and outlet valves in connection with a source of anesthetic gas and a breathing mask respectively, said valves being adapted to open and close independently of each other, the improvements which comprise a valve-actuating lever in the chamber cooperating with the inlet valve, a valve-actuating lever in the chamber 15 cooperating with the outlet valve, a cam housed in the casing to cooperate with said levers and shaped to rock the same independently of each other and in succession only, whereby both valves can never be simultaneously opened, and patient-operable means for actuating the cam.
- 20 25 8. An apparatus for the administration of an anesthetic gas under the control of a patient, comprising, in combination, a chamber having inlet and outlet valves in connection with a source of anesthetic gas and a breathing mask respectively, said valves being adapted to open 30 and close independently of each other, the improvements which comprise valve-actuating members in the chamber cooperating with the inlet and outlet valves individually, an actuating cam housed in the casing between said members 35 to cooperate with the same individually and shaped to actuate the same independently of each other and in succession only, whereby both valves can never be simultaneously opened, and patient-operable means for actuating the cam.
- 40 45 9. An apparatus for the administration of an anesthetic gas under the control of a patient, comprising, in combination, a chamber having inlet and outlet valves in connection with a source of anesthetic gas and a breathing mask 45 respectively, said valves being adapted to open and close independently of each other, the improvements which comprise valve-actuating members in the chamber cooperating with the inlet and outlet valves individually, a rotary actuating cam housed in the casing between said members 50 to cooperate with the same individually and shaped to actuate the same independently of each other and in succession only, whereby both valves can never be simultaneously opened, 55 means for limiting the movement of the cam in both directions, and patient-operable means for actuating the cam.
- 60 65 10. In an apparatus for administration of an anesthetic gas under the control of a patient, said apparatus comprising, in combination, a gas chamber, means for delivering anesthetic gas thereto including an inlet valve, means for delivering gas from the chamber to a breathing mask including an outlet valve, the improvements which 65 comprise means housed in the chamber and including a rotary cam to open said valves in succession only and prevent opening of both simultaneously, a pinion connected with the cam to rotate the same, a gear meshing with the pinion to rotate the latter, and patient-operable means outside of the casing to rotate the gear.

CERTIFICATE OF CORRECTION.

Patent No. 2,185,069.

December 26, 1939.

JUSTIN G. SHOLES, ET AL.

It is hereby certified that error appears in the printed specification of the above numbered patent requiring correction as follows: Page 2, second column, line 11, for "gas can" read gas that can; page 3, second column, line 1, claim 6, for "or" read of; and that the said Letters Patent should be read with this correction therein that the same may conform to the record of the case in the Patent Office.

Signed and sealed this 30th day of January, A. D. 1940.

(Seal)

Henry Van Arsdale,
Acting Commissioner of Patents.
